(57) **CLAIM**

The ornamental design for a distribution controller for air conditioner as shown and described.

DESCRIPTION

FIG. 1. is a perspective view of the front, right, and top sides of a distribution controller for air conditioner showing our new design;

FIG. 2. is a front view thereof;

FIG. 3. is a rear view thereof;

FIG. 4. is a left side view thereof;

FIG. 5. is a right side view thereof;

FIG. 6. is a top plan view thereof; and,

FIG. 7. is a bottom view thereof.

The broken lines in the drawings illustrate portions of the distribution controller for air conditioner that form no part of the claimed design.
